ELECTRIC GRILL AND BROILER COMBINATION

George B. Munsey, Little Rock, Ark.

Application May 13, 1957, Serial No. 46,120

Term of patent 14 years

(Cl. D81—10)

Fig. 1 is a front perspective view of an electric grill and broiler combination embodying my new design;

Fig. 2 is a top plan view thereof; and

Fig. 3 is a front elevational view of the electric grill and broiler combination.

The rear of the device is substantially plain aside from the electric cord.

I claim:

The ornamental design for an electric grill and broiler combination, substantially as shown and described.
